SPECIAL STITCH SEWING MACHINE

Mathias Pedersen, Valley Stream, N. Y., assignor
to American Machine & Foundry Company, a
corporation of New Jersey

Application April 10, 1948, Serial No. 20,198

32 Claims. (Cl. 112—171)

1

This invention relates to sewing machines, and more particularly to sewing machines capable of making special types of stitches either for decorative or utilitarian purposes, especially the type in which a double pointed needle, provided with a thread having a loose and a fixed end, is projected back and forth through the work fed either manually or automatically over a work supporting table into the range of action of the needle.

This invention consists further in improvements in sewing machines of the type illustrated in Johnson Patents 2,368,066; 2,386,800 and 2,389,151, and particularly to improvements in mechanisms for decorating coats of all types, men's and women's suits and other garments where this type of decoration is desired.

The mechanism constituting a part of the present invention which is useful in forming angle stitches, makes possible the formation of a particularly desirable angle stitch because of the fact that a larger proportion of the thread forming each stitch is disposed within the cloth being decorated, and also it is possible to make extremely fine stitches, such that the stitches made by this mechanism closely simulate hand "pricking."

The present invention also consists of improved mechanism for selectively producing various types of stitches at the will of the operator. It also includes novel mechanism for handling the thread and preventing it from being spitted or broken by the needle, or the thread puller which pulls the loose end of the thread through the work during the formation of each stitch.

It is therefore an object of my invention to provide an improved sewing machine having novel means for selectively changing from one type of stitch to another.

My invention consists further in the provision of a novel method of forming angle stitches, short and long stitches, and successions of normal or standard stitches, dependent upon the will of the operator and the type of work to be decorated, and in selectively operated mechanism for accomplishing these results.

The invention consists of a provision of improved angle stitch forming mechanism which is capable of more closely approximating hand sewing and wherein a variety of angle stitches can be made according to the wish of the operator and by the use of simple adjusting and changing devices.

A further object of the invention is to provide improved angle stitch forming mechanism and means for incapacitating this mechanism if it

is desired to discontinue angle stitching and form short and long or standard length over and under slip stitches. It has been found particularly desirable to be able to incapacitate the angle stitch mechanism during the decorating of a garment, especially in cases where it is desired to sew around sharp turns as in the corner of a lapel of a coat or the like. By the use of the improved mechanism of this invention, this result can be readily obtained.

The invention is also characterized by the provision of an improved thread trap and a thread support which are mounted beneath the work support table in relatively close proximity to the needle, and means for displacing of thread out of the path of the needle into a thread trap and onto the thread support, so that due to the operation of the thread puller which pulls the loose end of the thread through the work, the danger of breakage of thread is greatly minimized and substantially eliminated.

With these and other objects in view but not specifically mentioned, the invention consists in the novel method, and certain combinations and constructions which will be hereinafter fully described, and then set forth in the claims appended.

In the accompanying drawings which form a part of this specification and in which like characters of reference indicate the same or like parts:

Figure 1 is a side elevation of the improved angle stitch mechanism;

Figure 2 is a plan view of the same;

Figures 3 and 4 are detailed side elevations illustrating the actions of the angle stitch mechanism during operation;

Figure 4a is a view taken on line 4a—4a of Figure 4;

Figure 5 is an enlarged sectional side elevation illustrating the making of an angle stitch;

Figure 6 is an end elevation of the novel thread guide and trap mechanism;

Figure 7 is an isometric view showing the lower needle bar and thread guiding mechanism in action.

Referring to the drawings, and particularly Figures 1 and 2, the mechanism constituting the present invention is adapted primarily for use in the machine shown in the above referred to Johnson patents, although it may have use in other sewing machines capable of utilizing structure made in accordance with the invention. In Figure 1 it will be seen that there has been provided upper and lower needle bars 98, 100 re-

spectively, which project a double pointed needle N, having an eye located between the points, back and forth through material or work to be sewed and form therein a plurality of under and over type stitches. The eye of the needle is threaded with a thread which after the first stitch is made, has a fixed and a loose end. During the sewing operations and after the formation of each stitch, the loose end of the thread is pulled through the work in known manner. The mechanism for operating the needle bars, thread puller and other thread handling means in general can be of the same type as that described in the above referred to Johnson patents.

As is well understood in the art, double pointed needle N is grasped alternately by chucks 102 in needle bars 98 and 100, and projected back and forth with the thread through the work. Needle bars 98, 100 are mounted in brackets 99 connected to cam actuated levers (not shown) which reciprocate them in proper timed relation with the operation of the stitch forming mechanism 50 and other moving parts of the machine in order to form the desired types of stitches. Reference is made to Johnson Patent 2,368,066 which shows in detail suitable mechanism for operating the needle bars and coacting means for pulling the loose end of the thread through the work.

In order to advance work W over work supporting table 4, and position it properly thereon with respect to needle N, a presser foot 127 is provided. This foot carries a toe 131 mounted on pivot pin 133 in foot 127. A spring urged plunger 143 in a vertical bore 137 in foot 127 normally urges toe 131 downwardly to substantially horizontal position such as shown in Figure 3. The upward movement of toe 131 is limited by a stop 141 mounted on foot 127. Toe 131 is provided with two elongated portions 139 spaced apart a distance greater than the diameter of the needle. Elongated portions 139 overlie a portion of angle work shifting and lifting plate 52 for reasons described hereinafter. Presser foot 127 cooperates with an upper feeding foot 121 and a lower feed plate 123 provided with a conventional toothed work feeding dog 122. Plate 52 is provided with a cut out 53 which allows upper work feeding foot 121 and feeding dog 122 to coact, engage work to be fed while located upon plate 52 and travel it forwardly beneath raised needle N. The construction and operation of work feeding foot 121 and the operation of presser foot 127, except as mentioned above, can be substantially the same as that shown in Johnson Patent 2,389,151.

Referring to Figures 1, 2, 3, 4 and 5, the angle stitch forming mechanism designated generally 50 consists of a work shifting and lifting plate 52 mounted on or formed integrally with a bracket 54 fixed to a lever 56 slidably fulcrumed at one end on a cam follower 58 adapted to run in a slot or cam 60 in plate 62 pivotally mounted at 63 on bracket plate 64, mounted on bracket 66 suitably secured to frame 2 of the machine. The other end of lever 56 is pivoted to an arm 60, which functions as a pusher cam, is inclined downwardly to the left, as viewed in Figure 1. This arrangement provides what may be termed a "floating" mount for lever 56 which supports work inclining plate 52 of the angle stitch forming mechanism 50. The operation of plate 52 with respect to work W is such that, as shown in Figure 5, every time needle N is passed up-

wardly through the work, the portion of the work to be stitched is inclined at an acute angle with the path of travel of the needle therethrough. Preferably the work is positioned in a plane substantially parallel with the axis of the needle. This arrangement makes it possible to dispose the major portion of the thread forming each angle stitch in the work. At this time, toe 131 is raised to the position shown in Figures 4 and 5 due to the upward movement of plate 52.

When needle N is held by upper needle bar 98, plate 52 is returned to its inoperative or substantially horizontal position relative to work support table 4, as viewed in Figures 1 and 3. Feed foot 121 and feed bar 122 are then operated to advance the work beneath upraised needle N, and when needle bar 98 again moves downwardly, needle N is passed through substantially horizontally positioned work W completing the stitch.

The mechanism for operating plate 52 consists of an adjustable connecting rod 68, one end of which is secured at 70 to lever 56. The other end of rod 68 extends through a bore 72 in arm 74 of lever 75 pivotally mounted at 76 on bracket 78 suitably attached to frame 2. A collar 80 fastened to this end of rod 68, prevents its removal from bore 72. A collar 82 also attached to rod 68 forms an abutment which is engaged by the upper face of the portion of arm 74 encircling rod 68. A spring 84 encircling rod 68 engages collar 80 on rod 68 and the portion of the lower face of arm 74 which encircles rod 68. Spring 84 is employed to provide tension and allow arm 74 to continue its downward movement when plate 52 and the work held thereby press upwardly against toe 131 after the latter has engaged stop plug 141.

Cam 60, as viewed in Figure 1, is inclined downwardly and to the left. The provision of cam 60 makes it possible for plate 52 to be moved forwardly or toward needle N at the same time it is moving upwardly from its substantially horizontal position, as shown in Figures 1 and 3, to inclined position, as shown in Figures 4 and 5. In this way, the portion of the work to be stitched is moved toward the needle and also given a substantially simultaneous upward movement relative to the needle. The combined movements give the most efficient angular inclination of the portion of the work to be stitched relative to needle N. The final arrangement of thread T forming each complete stitch is illustrated in Figure 5.

Plate 62 is provided with an opening 65 in 55 which is located one end of a spring 67, the other end of which is seated in a bore 69 in support member 71 adjustably secured to plate 64 by clamp screw 73. A pin 77 on plate 62 projecting into an opening 79 in bracket plate 64, 60 limits turning movement of plate 62 due to the action of lever 56 and spring 67. Spring 67 provides a resilient mount for angle plate 52 such that, within reasonable limits, it can adapt itself automatically to the thickness of the work. 65 If wide changes occur in thickness of work being stitched, it may be necessary to readjust the position of support member 71.

Arm 86 of lever 75 is provided with a cam follower, such as roller 88 which runs on cam 70 90 fixed to shaft 205. A spring 92 having one end attached to arm 94 of lever 75, and its other end secured to bracket 93 on frame 2, maintains cam follower 88 in engagement with cam 90.

75 Shaft 205 is driven by gear 226 fixed thereto

(Figure 2) meshing with a gear (not shown) driven by mechanism which may be the same as that shown in Johnson Patent 2,386,800, granted October 16, 1945. Since the construction and operation of the driving mechanism do not form a specific part of the present invention, further illustrations and descriptions are omitted in the interests of brevity.

If it is desired to make a succession of standard over and under or slip stitches, wherein all stitches are of substantially the same length, angle mechanism 50 can be incapacitated. In this case, an angle stitch throw-out device is employed. A preferred type of mechanism for accomplishing this purpose is shown in Figures 1 and 2. Arm 94 of lever 75 is provided with a bore 104 through which extends a threaded end 105 of connecting rod 106 on which are secured nut 108 and lock nut 110. The other threaded end of rod 106 is adjustably secured in head 112 pivotally attached by pivot pin 115 to lever 114 fixed to shaft 118 supported by brackets 120 suitably attached to frame 2. A lever 124 fixed to shaft 118 is connected by an adjustable rod 125 to foot treadle 126. Adjustable stop screw 119 suitably mounted in lever 114 adapted to engage abutment 129 on frame 2, limits the downward movement of treadle 126.

Also attached to shaft 118 is a lock arm 128, which, when treadle 126 is depressed, engages a stop pin 130 on arm 132 secured to shaft or shank 134 of slotted cam member 136, described hereinafter, mounted for turning or oscillating movement in suitable bearings in frame 2 (Figure 2). Therefore when treadle 126 is depressed, arm 132 and shaft 134 cannot move and cam 136 is locked against movement. A spring 138 having one end attached to a reduced portion of pivot pin 115, and its other end fastened to a pin 140 mounted in a bracket 142 secured to frame 2 raises treadle 126 and disengages lock arm 128 from engagement with pin 130.

The size of stitch formed during the operation of angling mechanism 50 depends upon the adjustment of nuts 180, 182 which control the operating positions of slotted cam member 136. When nuts 180, 182 are adjusted in accordance with the length of stitch to be formed, and the machine is operating, slotted cam member 136 is oscillated to control the movement of lower feed bar 123 having secured thereto a toothed feed bar 122, which in known manner, is adapted to be moved upwardly through a slot in table 4 of the machine and coact with upper feed foot 121 and a presser foot 127 in feeding the work to and past needle N. After moving upwardly into engagement with the underside of the work, bar 122 is given a forward movement to advance it along the table beneath the raised needle. Following this movement, bar 122 moves downwardly disengaging the work, and back to a position where it is ready to travel upwardly again. The mechanism for effecting the desired movement of feeder bar 122 and its supporting lower feed bar 123 is substantially the same as that shown in Johnson Patent 2,368,066. However, in order to make clear the operation of the mechanism as used in this invention, a brief description is given.

Referring to Figures 1 and 2 of the drawings, one end of lower feed bar 123 is pivotally connected to link 214 pivotally connected to one arm of a bell-crank lever 216 mounted upon a suitable pivot 218. The other arm of bell-crank lever 216 is pivotally connected to a lever 220

provided with a cam follower 222 which rides in cam slot 135 in slotted cam member 136. The free end of lever 220 is provided with an elongated slot in which rides a cam roller 224 secured to a crank pin 226 projecting from cam 227 mounted on shaft 228.

Also pivotally connected to work feed bar 123 at 229 is one end of an adjustable link 230 having its other end pivotally attached at 232 to one arm of bell-crank lever 234 loosely mounted on shaft 134 of slotted cam member 136. The other arm of bell-crank lever 234 is provided with a cam follower 236 tracking cam 227. Shaft 228 is suitably driven in proper timed relation with the several operating parts of the machine so that the combined movement of bell-crank levers 216 and 234 results in the desired substantially four motion path of travel of the work feed bar 123 and toothed feed bar 122 carried thereby.

Concurrently with the operation of angle stitch forming mechanism 50, slotted cam member 136 is rocked to cause alternate stitches or stitches of substantially equal length to be formed. The oscillation of slotted cam member 136 is effected by means of cam 184 fixed to shaft 205. Tracking cam 184 is a cam follower 186 on lever 188 pivotally supported on stud 190 mounted on bracket 191 attached to frame 2. Slidably connected to the free end of lever 188 is a connecting rod 192 having a collar 194 fixed adjacent one end thereof. A spring 196 encircling rod 192 bears against one face of lever 188 and a collar 198 attached to rod 192. The other end of rod 192 extends through a bore in an angular extension 199 of a link 200, and into a bore 201 formed therein. Spring 202 encircling rod 192 presses against a face of extension 199 and collar 201 secured to the end of rod 192. Link 200 is pivotally connected to lever 179 on shaft 134 by an elongated pivot pin 204. A spring 206 having one end attached to lever 188 and the other secured to pin 208 mounted in bracket 210 mounted on frame 2, maintains cam follower 186 in constant engagement with cam 184.

It will be seen that for each revolution of cam 184, slotted cam member 136 is shifted between two limits, which, depending upon the adjustment of nuts 180, 182, results in the formation of alternate stitches of different length, or a succession of stitches of the same length.

Referring to Figure 1, it is evident that whenever treadle 126 is depressed, lever 75 is rocked in a clockwise direction, and cam follower 88 is moved out of engagement with cam 90. This action prevents the operation of angling mechanism 50, and, of course, movement of angling plate 52. Hence so long as treadle 126 is depressed, no angle stitches are formed. The machine however, continues to operate and forms a series of standard stitches.

The length of the standard stitches made at this time depends upon the angular position of arm 132 on shaft 134. As shown in Figure 1, when lock arm 128 engages pin 130 and clamps arm 132 against further movement, slotted cam member 136 is held in one position, and feed bar 122 has a predetermined limited horizontal movement. The position of arm 132 is pre-set to allow a predetermined length of stitch to be made when the machine is assembled. If the position of arm 132 is adjusted clockwise or counter-clockwise, a different length of standard stitch can be made. The selective change from angle stitch forming to standard stitch is especially valuable and desirable in stitching around sharp corners, as in the case of the points of a

at coat lapels. If angle stitches were to be made at this time, the spacing would be unsatisfactory and the sought for effect would be lost. However, since the angle stitching mechanism can be temporarily incapacitated, normal or standard stitches can be made around the sharp corners and a satisfactory spacing effected. As a general rule, the predetermined standard stitch length is approximately the length of thread visible on the exposed surface of angle stitched work.

At times it may be advantageous to discontinue the formation of angle stitches, and form only alternate long and short stitches. This change can be effected by mounting a hook 209 on a pivot pin 211 on lever arm 86. When lever arm 86 is moved to disengage cam follower 88 from cam 90, and hook 209 is moved into engagement with pin 212 on frame 2, angle stitch mechanism 50 will be locked out of operation. In this case continued rotation of shaft 205 and cam 184 thereon will cause rod 192 to be reciprocated and alternate long and short stitches will be formed.

The length of stitches formed can be adjusted by changing the position of slotted cam member 136. As shown in Figures 1 and 2, two adjusting rods 250, 252 are provided. One end of each of these rods is threaded in order to accommodate adjusting nuts 180, 182 respectively. Adjusting nut 180 is provided with a reduced portion 181 which fits in an opening in bracket 185 attached to bracket 191. Adjusting nut 182 is formed with a similarly reduced portion 183. A plate 181 is suitably attached to the under face of bracket 185. In this manner nuts 180, 182 are maintained in operating position.

If desired, the end portion of threaded rods 250, 252 can be provided with spaced lines or calibrations 253 which indicate the length of stitch required. Formed on the other ends of rods 250, 252, or suitably attached thereto, are elongated heads 254, 256, having slots 258, 260 through which extends pivot pin 204.

It is evident that when either or both screws 180, 182 is turned, either clockwise or counter clockwise on its respective rod, head 254 and/or head 256 will be moved to the left or right, as viewed in Figure 2, depending upon the direction in which nuts 180 and/or 182 is turned. This adjustment will cause the ends 258 and 260, or 261 and 263 of slots 258 and 260, respectively, to limit the swing of pivot pin 204 under the action of cam 184 depending upon the type of long or short stitches desired, and whether a long or short stitch is to appear on the exposed surface of the work. The provision of elongated slots 258, 260 in heads 254, 256 makes possible the provision of controlled amounts of lost motion necessary to the formation of predetermined short and/or long stitches. If a succession of stitches of the same length is required, nuts 180, 182 are adjusted so that pin 204 is prevented from oscillating, whereupon slotted cam member 136 is maintained in its adjusted position during the time the machine is being operated.

Obviously, by means of the adjusting structure described, the position of slotted cam member 136 can be so adjusted that a wide variety of stitch lengths can be made. It is evident that horizontal movement of lower feed bar 123 is at a minimum when cam slot 135 is substantially horizontal and the shortest stitch is made. When cam slot 135 is vertical, the throw of bar 123 is at a maximum and the longest stitch can be formed.

During the operation of the machine when the adjustment of nuts 180, 182 allows the position of cam slot 135 to shift, it is evident that alternate stitches of different lengths will be formed. By suitably adjusting the position of nuts 180, 182, the length of thread visible on the surface of the work being stitched, may be shorter than that portion of the thread forming the next stitch on the undersurface of the work, or vice versa.

It is important to maintain the thread out of the path of movement of the needle beneath table 4 and prevent spitting of the thread by the needle, or twisting of the thread thereabout as needle N moves upwardly towards the work, which would cause loss of time due to thread breakage. In order to overcome this difficulty, improved thread guiding and handling mechanisms are provided.

As shown in Figures 1, 3, 4, 6 and 7, operating in conjunction with the stitch forming mechanism described hereinabove, and functioning to control the thread while the loose end L is being pulled through the work W by thread puller 203, is an improved thread guide and trap device designated generally 270. See Figures 5 and 6. This device consists of a thread guide, which may be a rod 272, suitably attached to and projecting outwardly from member 271 secured to frame 2. Thread guide and trap device 270 is positioned above the thread supporting drum 209. Thread puller 203 and the thread supporting drum 209, indicated in Figure 3, are of the same construction and operate in the same manner as shown in Johnson Patent 2,368,066. Rod 272 is formed with a substantially horizontal part 273 and a downwardly inclined part 274.

Mounted on member 271 above guide rod 272 is a co-operating trap forming a guide such as rod 276. Rod 276 is provided with a substantially horizontal portion 271, a substantially vertical part 278, a portion 279 parallel to part 273 of rod 272, and a turned up nose portion 280. Secured at 282 to frame 2 beneath table 4 is a thread lint trap and guide 284 provided with a vertical flange 286 and a substantially horizontal plate section 288 which catches lint dropping from the work and thread as the result of needle N moving with the thread through the work. Plate section 288 has a cut out portion 289 which allows lower needle bar 100 to move up and down beneath table 4. It is also provided with an upstanding projection 290 which tends to hold lint on plate section 288, and a tapered thread guide 292.

During the operation of thread puller 203 about drum 209 in dotted lines in Figure 3, in pulling the loose end L of thread T through work W, the thread is initially disposed as at I in Figure 7. However, when needle N is moved upwardly, this end of the thread is displaced laterally rearward to the position indicated at II wherein it is guided up the inclined face of guide 292 into the space between the rear face of guide 292 and flange 286. At the same time the thread is moved between rods 272 and 279 and upwardly into the space between rod portion 278 and frame 2, where it is held by finger 294 on thread shifting or displacing member 296. While so held, the loose end of the thread is clear of the path of movement of needle N. When thread puller 203 has completed its thread pulling operation in which the loose end L of the thread is disposed on the thread receiving drum (not shown), displacing member 296 moves from the

position shown in broken lines in Figures 6 and 7 to that shown in full lines.

Thread displacer 296 is pivotally mounted on a pin 298 in lever 300 fulcrumed at 302 on an extension of frame 2. The other end of thread displacer 296 is pivotally connected to lever 304 swingably mounted on a stud 306 supported by a bracket 308 suitably mounted on the frame of the machine. A cam follower 310 on lever 304 runs in a cam track in drum cam 312 on shaft 205 so designed that displacer 296 and hence finger 294 engages the thread at the proper time in order to function in the manner described.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a sewing machine having a work support table, mechanism for feeding work to be stitched over said table, and a needle bar adapted to project a needle with a thread through said work, a movable work shifting plate, means normally maintaining said plate positioned substantially in the plane of said table, and means for inclining said plate to position a portion of the work supported by said table at an angle to the plane of said table prior to the passage of said needle and thread through said work.

2. In a sewing machine having a work support table and a needle bar adapted to project a needle and a thread through work to be stitched on said table, a movable work shifting plate, operating mechanism for moving said plate into an angular position relative to said table to locate a portion of the work supported by said table at an angle thereto prior to the movement of said needle with said thread through said inclined portion of said work, and selectively operated means for incapacitating said plate, said means including a manually operated locking member, and means operative while said plate is incapacitated by said member for forming normal over and under stitches.

3. In a sewing machine having a work support table, a needle bar adapted to pass a needle and a thread through work supported by said table, and mechanism for feeding said work over said table into the path of movement of said needle, a work shifting plate, a movable support for one edge of said plate, and means for swinging said support during the formation of alternate stitches to raise one edge of said plate out of the plane of said table and incline a portion of the work supported by said table and plate at an angle to said table.

4. In a sewing machine having a work support table, a needle bar adapted to pass a needle and a thread through work supported by said table, and mechanism for feeding said work over said table into the path of movement of said needle, a work shifting plate, a movable support for one edge of said plate, means for swinging said support to raise the opposite edge of said plate out of the plane of said table and thereby incline a portion of the work supported by said table and plate at an angle to said table, a presser foot adapted to press said work upon said table and plate, and a pivoted yielding section carried by said presser foot constructed and arranged to yield upwardly when said plate is swung to said inclined position relative to said table.

5. Angle stitch forming mechanism for a sewing machine comprising a work support table, a needle bar adapted to project a needle and a thread through work to be stitched, a work inclining plate, a mount for said plate, means normally positioning said plate substantially in the plane of said table, and mechanism operative prior to the passage of said needle and thread through said work for moving said mount to incline said plate at an angle to said table whereby a portion of the work supported thereby is disposed at an acute angle to said needle.

6. Angle stitch forming mechanism for a sewing machine having a needle bar adapted to project a needle and thread through work to be stitched, and mechanism for feeding work to and from said needle; a pivoted plate, means for moving said plate to incline a selected portion of said work at an angle to the path of travel of said needle, and means operative after said needle has passed through said work and prior to the next movement of said needle for positioning said plate in a substantially horizontal plane.

7. In mechanism of the type defined in claim 6, means for moving said plate and the portion of work inclined thereby toward said needle prior to the movement of said needle through said inclined portion of said work.

8. In mechanism of the type defined in claim 6, means for moving said plate and the portion of work inclined thereby toward said needle prior to the movement of said needle through said inclined portion of said work, and selectively operated means for incapacitating said last named means, whereby a succession of normal over and under stitches can be formed.

9. Angle stitch forming mechanism for a sewing machine having a needle bar adapted to project a needle and thread through work to be stitched, and mechanism for feeding work to and from said needle, a member constructed and arranged to engage the underside of work to be stitched and incline a selected portion thereof at an angle to the path of travel of said needle and means for moving said member and the portion of work inclined thereby toward said needle prior to the movement of said needle through said inclined portion of said work, a presser foot for maintaining said work on said member, and a yielding mount constructed and arranged to allow said presser foot to pivot upwardly into an angular position relative to said inclined portion of said work.

10. In a sewing machine of the type provided with opposed needle bars adapted to operate alternately and project a double pointed needle and a thread having a fixed and a loose end through work to be stitched, a work support table having an opening, a work inclining member, mechanism for positioning said member in inoperative position in said opening in said table during a portion of the operation of said machine, including means for moving said member upwardly beneath

a portion of said work adjacent the path of travel of said needle to locate said portion of said work at an acute angle with said needle, means for moving said member towards said needle, and means operative to move one of said needle bars to project said needle through said angularly positioned work portion.

11. In a sewing machine, stitch forming mechanism, comprising a work shifting member, a movable mount for said member, a slotted cam track, a cam follower on said mount engaging

said track for controlling the movement of said mount, and means for moving said mount to travel said cam follower along said cam track to impart a combined upward and longitudinal movement to said member whereby a portion of work to be stitched is positioned at an angle with the horizontal.

12. In a sewing machine, stitch forming mechanism, comprising a work shifting member, a movable mount for said member, a cam coacting with said mount for controlling the movement of said mount, and means for moving said mount along said cam to impart a combined upward and longitudinal movement to said plate whereby a portion of work to be stitched is positioned at an angle with the horizontal.

13. In a sewing machine, stitch forming mechanism comprising a work shifting plate, a support for said plate, a movable mount for said support, a cam follower on said mount, a slotted cam track engaged by said cam follower on said mount, and means for moving said mount to travel said cam follower along said cam to impart a combined upward and longitudinal movement to said plate whereby a selected portion of work to be stitched is positioned at an angle with the horizontal.

14. In a sewing machine, the combination with a work support table, of a needle and opposed needle bars adapted to project said needle with said thread through work to be stitched, work feeding mechanism for moving said work over said table to and past said needle, a work shifting member, a support for said member constructed and arranged to maintain said member in inoperative position substantially in the plane of said table during a portion of each cycle of operation of said machine, and operating mechanism for alternately moving said member upwardly out of the plane of said table against the underside of a limited portion of said work to dispose said portion of said work angularly relative to the plane of said table prior to the movement of said needle through said angularly positioned portion of said work.

15. Angle stitch forming mechanism for a sewing machine provided with a work support table, and opposed needle bars for alternately projecting a double pointed needle and a thread back and forth through work to be stitched; a work shifting plate mounted in an opening in said table, means operative when said needle is held by one of said needle bars beneath said table for moving said plate upwardly to incline a selected portion of said work at an angle with the path of travel of said needle, and means adapted to move said last named needle bar upwardly through said inclined portion of said work.

16. In mechanism of the type defined in claim 15, means operative after the passage of said needle through said inclined portion of said work for moving said plate downwardly into said opening in said table, work feeding means, and means for operating said work feeding means to advance said work past the path of travel of said needle prior to the downward movement of said needle and while said plate is located in said opening.

17. Angle stitch forming mechanism for a sewing machine comprising a work shifting plate, a support for said plate, a movable mount for said support, a cam for controlling the movement of said mount, means for moving said mount along said cam to impart a combined upward and longitudinal movement to said plate whereby

a selected portion of work to be stitched is positioned at an angle with the horizontal, work feeding mechanism, means for operating said work feeding mechanism after a needle has been projected through said selected portion of said work to advance said work past the path of travel of said needle, and means for controlling the amount of movement of said work feeding mechanism to vary the length of stitch to be made in said work.

18. In a mechanism defined in claim 17, selectively operated mechanism for incapacitating said means for moving said mount whereby normal over and under stitches are made.

19. Stitch length controlling mechanism comprising a work feeding device, means for operating said work feeding device to move work to be stitched into and out of the path of movement of a needle, an oscillatable shaft, a work feeding mechanism control device mounted on said shaft, a lever attached to said shaft, an operating link attached to said lever, a cam actuated lever attached to one end of said link, an elongated adjusting pin projecting from said first-named lever, an adjusting rod having a slot through which said pin extends, a second adjusting rod having a slot through which said pin extends, and means for adjusting the position of said slots in said rods relative to said pin to control the limits of oscillation of said control device.

20. Stitch length controlling mechanism for a sewing machine work feeding device comprising means for operating said device for feeding work into and out of the range of operation of a reciprocating needle, an oscillatable shaft, a work feed control member mounted on said shaft, a lever secured to said shaft, a cam actuated lever, a link connecting said first-named lever and said cam actuated lever, said link being provided with resilient take-up connections, means for adjusting the limits of movement of said work feed control member for forming alternate stitches of predetermined length.

21. In a stitch length controlling mechanism as defined in claim 20, a lock for locking said work feed control member to make uniform stitches of a predetermined length, said lock comprising a lock arm on-said shaft, and a selectively operated member movable into engagement with said arm to prevent substantial movement of said feed control member.

22. The method of forming angle stitches in work to be stitched comprising moving work to be stitched into the range of operation of a needle, inclining a limited selected portion of said work at an angle to the plane of the main portion of said work and a substantially simultaneously therewith advancing said inclined portion of said work towards the path of travel of said needle, and while said limited selected portion of said work is so inclined and on one movement only of said needle passing said needle through said inclined portion of said work.

23. The method of forming angle stitches in work to be stitched comprising moving work to be stitched into the range of operation of a needle, inclining a limited selected portion of said work at an angle to the plane of the main portion of said work and substantially simultaneously therewith advancing said inclined portion of said work towards the path of travel of said needle, passing said needle through said inclined portion of said work on one movement of said needle, moving said stitched portion of said

work away from the path of said needle and on the next movement of said needle passing said needle substantially at right angles through said work prior to the formation of the next angle stitch.

24. The method of forming stitches in work to be stitched comprising moving said work into the range of operation of a needle, alternately inclining a limited selected portion of said work at an acute angle to the path of travel of said needle and substantially simultaneously therewith advancing said inclined portion of said work towards said path of travel of said needle, passing said needle in one direction through said inclined portion of said work, positioning said stitched portion of said work in a substantially horizontal plane substantially coplanar with a portion of the unstitched work, moving said stitched portion of said work away from the path of travel of said needle, passing said needle in the opposite direction substantially at right angles to said substantially horizontally positioned work to complete said stitch, selectively maintaining said work being stitched in a substantially horizontal plane and forming a plurality of over and under stitches therein, controlling the amount of movement of each portion of said work to be stitched past the path of travel of said needle in order to control the length of stitch formed therein, and again alternately inclining portions of said work at an acute angle to the path of travel of said needle to dispose thread therein at an angle to the surfaces of the work being stitched.

25. In a sewing machine, a work feeding mechanism, means for operating said work feeding mechanism to move work to be stitched into and out of the path of movement of a needle, means adapted to engage one surface only of selected portions of said work and incline said portions of said work at an acute angle to the path of travel of said needle through said work, a work feeding mechanism control device, and means for adjusting said control device to vary the length of stitch being formed in said work.

26. In a sewing machine of the type provided with opposed needle bars adapted to operate alternately and project a double pointed needle and a thread having a fixed and a loose end through work to be stitched, a work support table having an opening, a work inclining member, mechanism for positioning said member in inoperative position in said opening in said table during a portion of the operation of said machine, including means for moving said member upwardly beneath a portion of said work adjacent the path of travel of said needle to locate said portion of said work at an acute angle with said needle, means for moving said member towards said needle, means operative to move one of said needle bars to project said needle through said angularly positioned work portion, an oscillatable shaft, a work feeding mechanism control device mounted on said shaft, a lever attached to said shaft, an operating link attached to said lever, a cam actuated lever attached to one end of said link, an elongated adjusting pin projecting from said first-named lever, an adjusting rod having a slot through which said pin extends, a second adjusting rod having a slot through which said pin extends, and means for adjusting the position of said slots in said rods relative to said pin to control the limits of oscillation of said control device.

27. In a machine as defined in claim 26, means

for incapacitating said member during selected periods of operation of said machine whereby a succession of over and under stitches is formed in said work.

5 28. In a stitch forming mechanism for a sewing machine, a work support table, a needle bar adapted to project a needle and a thread through work to be stitched, a tiltable work inclining plate, operating mechanism for said plate, comprising means for alternately positioning said plate substantially in the plane of said table, and for inclining said plate upwardly against the underside of selected limited portions of said work to incline said portion of said work at an angle with the horizontal during the formation of alternate stitches in said work.

10 29. In a stitch forming mechanism for a sewing machine, a work support table, a needle bar adapted to project a needle and a thread through work to be stitched, a tiltable work inclining plate, operating mechanism for said plate, comprising means for alternately positioning said plate substantially in the plane of said table, and for inclining said plate upwardly against the underside of selected limited portions of said work to incline said portion of said work at an angle with the horizontal during the formation of alternate stitches in said work, said mechanism including a cam, a cam lever having a follower tracking said cam, and a link connecting said lever and said plate.

15 30. In a stitch forming mechanism for a sewing machine, a work support table, a needle bar adapted to project a needle and a thread through work to be stitched, a tiltable work inclining plate, operating mechanism for said plate, comprising means for alternately positioning said plate substantially in the plane of said table, and for inclining said plate upwardly against the underside of selected limited portions of said work to incline said portion of said work at an angle with the horizontal during the formation of alternate stitches in said work, said mechanism including a cam, a cam lever having a follower tracking said cam, a link connecting said lever and said plate, and a resilient connection between said link and lever constructed and arranged to maintain said plate in yielding engagement with each portion of said work inclined thereby.

35 31. In a stitch forming mechanism for a sewing machine, a work support table, a needle bar adapted to project a needle and a thread through work to be stitched, a tiltable work inclining plate, operating mechanism for said plate, comprising means for alternately positioning said plate substantially in the plane of said table, and for inclining said plate upwardly against the underside of selected limited portions of said work to incline said portion of said work at an angle with the horizontal during the formation of alternate stitches in said work, said mechanism including a cam, a cam lever having a cam follower tracking said cam, and a link connecting said lever and said plate, a manually operated rod connected to said lever for selectively moving said follower away from said cam to prevent movement of said plate to inclined position.

40 32. In a stitch forming mechanism for a sewing machine, a work support table, a needle bar adapted to project a needle and a thread through work to be stitched, a tiltable work inclining plate, operating mechanism for said plate, comprising means for alternately positioning said plate substantially in the plane of said table,

45 75 70

and for inclining said plate upwardly against the underside of selected limited portions of said work to incline said portion of said work at an angle with the horizontal during the formation of alternate stitches in said work, said mechanism including a lever having a cam follower tracking said cam, and a link connecting said lever and said plate, a manually operated device connected to said lever for moving said follower away from said cam to interrupt temporarily the formation of stitches through inclined portions of said work, whereby relatively short over and under stitches are formed, and other means for preventing the movement of said plate whereby a succession of normal over and under stitches can be formed.

15 MATHIAS PEDERSEN.
